UNITED STATES PATENT OFFICE.

OTTO A. JIRANEK, OF GRAND RAPIDS, MICHIGAN, ASSIGNOR TO SEARS, ROEBUCK AND CO., OF CHICAGO, ILLINOIS, A CORPORATION OF NEW YORK.

DESIGN FOR A SEWING-MACHINE CABINET.

• 60,789.

Specification for Design.

Patented Apr. 11, 1922.

Application filed October 12, 1921. Serial No. 507,381. Term of patent 3½ years.

To all whom it may concern:

Be it known that I, Otto A. JIRANEK, a citizen of the United States, residing at Grand Rapids, in the county of Kent and State of Michigan, have invented a new, original, and ornamental Design for Sewing-Machine Cabinets, of which the following is a specification, reference being had to the accompanying drawing, forming part thereof.

The figure is a perspective view of a sewing machine cabinet showing my new design.

I claim:

The ornamental design for a sewing machine cabinet, as shown.

OTTO A. JIRANEK.
